DOOR CHECK MECHANISM

George H. Logan, Chicago, Ill., assignor, by mesne assignments, to George W. Housby, Jr., Chicago, Ill.

Application July 13, 1950, Serial No. 173,629

4 Claims. (Cl. 16—49)

1

This invention relates generally to door check mechanisms and more particularly to those door check mechanisms in which an operating unit is adapted to mounting in the floor or building structure adjacent the end of a door, and which door check mechanism includes an arm secured to the door for providing a door mounting and operating connection to the operating unit.

One of the general objects of this invention is to provide, in a door check mechanism, coacting parts by which a door is connected to an operating unit, and which parts are constructed and arranged to afford ease of door installation and adjustment.

More specifically and in one aspect, my invention comprehends the provision of a door supporting arm having a socket therein for receiving the spindle of an operating unit, which socket fits the spindle with relative snugness in a direction lateral to the plane of the door and is elongated in a direction parallel to the plane of the door, thereby to provide for ease of mounting the door on the spindle.

As another object, my invention has within its purview the provision of a door supporting arm adapted to mounting on the spindle of an operating unit and including adjustable elements by which the angular position of the door may be readily and quite precisely adjusted in reference to the spindle when the door is in place on the spindle.

My invention has for a further object the provision of an arm by which a door is secured to the spindle of an operating unit of a door check mechanism and which includes a part readily accessible when the door is mounted for adjusting the height of the door relative to the spindle.

Other objects and advantages of the invention will be apparent from the following description and the accompanying drawing in which similar characters of reference indicate similar parts throughout the several views.

Referring to the one sheet of drawing:

Fig. 1 is a fragmentary plan view of a door check mechanism embodying a preferred form of my invention and wherein the position of a door in relationship thereto is illustrated fragmentarily by dot and dash lines;

Fig. 2 is a fragmentary side elevational view of the structure depicted in Fig. 1;

Fig. 3 is an end sectional view wherein the section is taken substantially on a line 3—3 of Fig. 2 and in the direction indicated by arrows;

Fig. 4 is a fragmentary top sectional view, drawn to an enlarged scale and wherein the sec-

2

tion is taken substantially on a line 4—4 of Fig. 2 and in the direction of the arrows; and

Fig. 5 is a fragmentary side sectional view taken substantially as indicated by a broken line 5—5 and accompanying arrows in Fig. 1.

In the exemplary embodiment of my invention which is shown herein for illustrative purposes, the disclosed door mechanism embodies an operating or control unit 10 which may, for example, 10 be of the type and general structure shown in the co-pending application of Martin Carlson, Serial No. 139,831, filed January 21, 1950, now Patent No. 2,585,625, dated February 12, 1952, and entitled Door Check Mechanism. Considered 15 generally for the purposes of this application, the operating or control unit 10 is adapted to mounting in flush relationship to the floor of a building at one side of a door opening. The operating and control mechanism thereof is enclosed within 20 a housing 12 and acts through a rotatable spindle 13 for supporting and controlling the movements of a door 14, the axis of the spindle 13 being located substantially on the hinge axis or axis of swinging movement of the door. Acting through 25 the spindle 13, the operating and control unit 10 tends normally to hold the door in a closed position in the general plane of a door frame, returns the door to its closed position at controlled rates after it is swung to an open position, and may 30 releasably retain the door in a wide open position.

In the installation of a door with a door check mechanism of the type herein referred to, it is desirable, in addition to the adjustments provided in the operating unit itself, to provide for the ease 35 of placement and adjustment of the door upon the spindle 13 of the operating unit. For such purposes, I have provided an arm 15 having a relatively thin elongate portion 16 adapted to be secured to a surface of the supported door. In 40 the present instance, the elongate portion 16 of the arm is adapted to extend along the bottom edge of the supported door and has a series of spaced openings 17 therein through which fastening means, such as screws, extend to secure the door in position thereon. At one position and at 45 one end of the elongate portion 16 of the arm, the head portion 18 is integrally formed thereon and projects laterally therefrom.

The outer end of the head portion 18 of the arm is of relatively thick section and has a socket 19 extending inwardly from its lower surface in a direction lateral to the longitudinal dimension of the elongate portion 16 of the arm. The left-hand cylindrical half of the socket as viewed 55 in Figs. 1 and 4 is concentric with and of a

size to fit the corresponding cylindrical end portion of the spindle 13 with relative snugness. The other half portion of the socket is elongated from true circular shape in cross section as shown in Figs. 1 and 4 so as to provide for ease of mounting the door upon the spindle 13 when the arm 15 is secured to the door. It may be readily understood that in effecting the mounting of a door upon a spindle, it is much easier to locate the socket and for the door to drop into place with the socket elongation thus provided in one plane. Since it is generally easier to effect lateral placement of the door, I prefer to have the elongation of the socket in a direction parallel to the elongate portion of the arm and thus parallel to the general plane of the door. Furthermore, by having the elongation in only one plane, the arm may be locked in position and precisely located without a plurality of relatively angularly disposed locking elements.

For providing adjustment of the elevation of the door to which the arm is secured, I have provided a set screw 20 which is threaded into a bore 22 at the upper end of the socket. The bore 22 is preferably smaller than the diameter of the socket and adjoins the socket in a direction parallel to the axis thereof. By adjusting the position of the set screw 20, which abuts the end of the spindle 13, as shown in Fig. 5, the elevation of the arm is varied in respect to the spindle.

As shown in Figs. 4 and 5, a flat surface 23 is provided on one side of the spindle at the end thereof which fits into the socket. This surface, in the disclosed embodiment, and by preference, normally faces in the direction of elongation of the socket 19. Substantially parallel bores 24 and 25 extend through the side wall of the head portion 18 of the arm and open into the socket 19 on opposite sides of the socket axis. As shown, these bores have axes which are substantially parallel to the elongate portion of the arm and are also substantially parallel to the axis of elongation of the bore 19. Set screws 26 and 27 are threaded into the bores 24 and 25 respectively and have inner end portions which are adapted to engage the flat surface 23 of the spindle when the arm is in place with the spindle in the socket.

After the arm has been placed upon the spindle and a proper setting of the set screw 20 has been effected to establish the proper door height, the set screws 26 and 27 may be tightened. The latter set screws not only serve to lock the arm in place upon the spindle, but also may be adjusted to effect an angular adjustment of the arm position relative to the spindle. It may be readily understood that by loosening one of the set screws and tightening the other, the adjusted position of the arm relative to the spindle may be varied between positions such as those indicated at 15 and 15a in Fig. 4. By the use of this adjustment, together with those normally provided in the operating mechanism, the position and movements of the door can be regulated so that it is in proper relationship to the door frame when closed, and avoids engagement with obstructions and the like in the wide open position.

From the foregoing description and reference to the accompanying drawings, it may be understood that I have provided a door mounting structure which not only increases the ease of mounting the door upon the operating unit of

a door check mechanism, but which also provides readily accessible and easily adjusted parts for determining the elevation and normal angular position of the door relative to the spindle of the operating unit.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In a door check mechanism which acts through a rotatable vertical spindle having a flat side portion thereon to support and control the movements of a door, the combination comprising an arm having an elongate door supporting portion adapted to extend along and be secured to a surface of a door, said arm also having a head portion projecting angularly to one side of the elongate portion and having a socket therein with a vertical axis for receiving the spindle, and a plurality of set screws threaded into the head portion of the arm and extending laterally into the socket for abutment with the flat side of the spindle on opposite sides and transversely of the socket axis, so that the position of the arm may be adjusted angularly with reference to the spindle by changing the positions of the set screws.

2. In a door check mechanism which acts through a rotatable vertical spindle having a flat side portion thereon to support and control the movements of a door, the combination comprising an arm having an elongate door supporting portion adapted to extend along and be secured to a surface of a door, said arm also having a head portion projecting angularly to one side of the elongate portion and having a socket therein with a vertical axis for receiving the spindle, said socket being elongated in a direction substantially parallel to the elongated portion of the arm, and a plurality of set screws threaded into the head portion of the arm and extending laterally into the socket for abutment with the flat side of the spindle on opposite sides and transversely of the socket axis, so that the position of the arm may be adjusted angularly with reference to the spindle by changing the positions of the set screws.

3. In a door check mechanism which acts through a rotatable vertical spindle having a flat side portion thereon to support and control the movements of a door, the combination comprising an arm having an elongate door supporting portion adapted to extend along and be secured to a surface of a door, said arm also having a head portion projecting angularly to one side of the elongate portion and having a socket therein with a vertical axis for receiving the spindle, a screw threaded into the head portion of the arm and extending axially into the socket for abutment with the end of the spindle to effect adjustment of the position of the arm axially of the spindle, and a plurality of set screws threaded into the head portion of the arm and extending laterally into the socket for abutment with the flat side of the spindle on opposite sides and transversely of the socket axis, so that the position of the arm may be adjusted angularly with reference to the spindle by changing the positions of the set screws.

4. In a door check mechanism which acts through a rotatable vertical spindle having a flat side portion thereon to support and control the movements of a door, the combination comprising an arm having an elongate door supporting portion adapted to extend along and be secured to a surface of a door, said arm also having a head portion projecting angularly to one side of the elongate portion and having a socket therein with a vertical axis for receiving the spindle, said socket being elongate in a direction substantially parallel to the elongate portion of the arm, a screw threaded into the head portion of the arm and extending axially into the socket for abutment with the end of the spindle to effect adjustment of the position of the arm axially of the spindle, and a plurality of set screws threaded into the head portion of the arm and extending laterally into the socket for abutment with the

flat side of the spindle on opposite sides and transversely of the socket axis, so that the position of the arm may be adjusted angularly with reference to the spindle by changing the positions of the set screws.
